UNITED STATES PATENT OFFICE.

JAMES M. CONNER, OF NEW YORK, N. Y.

DESIGN FOR A FONT OF PRINTING-TYPE.

SPECIFICATION forming part of Design No. 14,405, dated November 13, 1883.

Application filed September 14, 1883. Term of patent 14 years.

To all whom it may concern:

Be it known that I, JAMES M. CONNER, of the city, county, and State of New York, have invented and produced a new and original 5 Design for a Font of Printing-Type, of which the following is a specification.

The nature of my design is clearly shown in the accompanying typographic impression, to which reference is made; and it consists of an 10 unshaded letter, the lower portion of which is heavier than the upper portion, ornamented by a series of flourishes extended below the letters, curving to the right and terminating in the heavy dot, except in the C, J, N, P, and 15 V, in which the flourishes curve to the left. The A, C, E, F, G, L, S, T, and Z are further ornamented by the light curved line with heavy

dot termination, which occurs at the upper part of the letters, and the B, D, P, and R by the heavy dot, as shown. 20

The character of the design is preserved in the figures, the flourishes being found in the 1, 4, and 7, and in the lower-case, save that the flourishes are omitted, notably in the e, f, g, j, r, s, t, x, and z. 25

Having now described my invention, I claim as new—

The design for a font of printing-type, substantially as shown and described.

JAMES M. CONNER.

In presence of—

W. V. H. HICKS,
A. SIDNEY DOANE.
